UNITED STATES PATENT OFFICE.

ALFRED JAMES JUNG, OF KINGSTON-UPON-THAMES, ENGLAND.

INTERNAL-COMBUSTION MOTOR.

1,324,159.

Specification of Letters Patent.

Patented Dec. 9, 1919.

Application filed July 8, 1919. Serial No. 309,523.

To all whom it may concern:

Be it known that I, ALFRED JAMES JUNG, subject of the King of Great Britain, residing at Thames street, Kingston-upon-

5 Thames, in the county of Surrey, England, have invented certain new and useful Improvements in or Relating to Internal-Combustion or Explosion Motors or Engines, of which the following is a specification.

10 This invention relates to internal combustion or explosion engines or motors particularly of the class known as two-stroke engines or motors, and the chief object of the invention is to increase their efficiency and

15 improve and simplify their construction.

According to the present invention the inlet and exhaust ports or openings of the cylinder, or of each cylinder, are controlled by one or more sliding or reciprocating members 20 or a sleeve arranged outside the cylinder cooling chamber or water jacket so as to be uninfluenced by heat, and operated by or simultaneously with the piston. According to the present invention also there is provided, at the outer end of the cylinder, a chamber the end walls of which are formed respectively by the end of the cylinder and a flange on the outer end of the piston, and the movement of the piston with its flange 25 causes the formation in the chamber of a partial vacuum so that on communication being established between the combustion chamber and this chamber, at or about the end of the explosion stroke and conveniently 30 through a port controlled by the piston, the residue of the spent gases is withdrawn and a fresh combustion charge induced, due to the reduced pressure in the cylinder. On the return or compression stroke, the gases 35 in the vacuum chamber are expelled through a port controlled by one or other of the aforesaid sliding members or the sleeve. In accordance with the present invention also the cylinder with its cooling jacket, in place 40 of being bolted down to its bed plate or base as is usual, is suspended by its inner end within a surrounding casing secured to the bed plate and between the inner walls of which and the outer walls of the cylinder 45 jacket is a space for the aforesaid sliding member or members.

Referring to the accompanying drawings which show in sectional elevation, a cylinder or unit of an internal combustion engine embodying the present invention,

A is the sliding member or sleeve, B the

cylinder, C the water jacket or cooling chamber, D the piston, E the vacuum chamber.

The cylinder B is provided with an inlet 60 port or opening B', exhaust ports B² B⁴ communicating with the atmosphere and an exhaust port B³ communicating with the vacuum chamber E.

In the embodiment illustrated the inlet 65 and exhaust ports B¹ B² B⁴ are controlled in proper succession and in time relation by a single sliding member or sleeve A located between the outer walls C of the water circulating chamber C' and an outer casing F. The walls of the chamber C' are so devised 70 that the chamber is located entirely within or does not project beyond the lines of the cylinder. The valve-controlling sleeve A by the arrangement shown is removed from the 75 heating effects of the cylinder and is uninfluenced by them.

The sleeve A is secured directly to the piston D by having its lower end fixed in any convenient manner to a flange D' on the 80 outer end of the piston; the port controlling sleeve A is thus moved directly by and simultaneously with the piston D and there is no relative movement between them.

The inlet port B' of the cylinder communicates with a fuel supply pipe G g by means of a conduit b which passes through the water chamber C, and in the sliding sleeve A is an opening A' which at the requisite point in the stroke or cycle opens 85 communication between the port g leading to the pipe G and the conduit b leading to the port B'.

The piston D is driven outward due to the explosion in the combustion chamber B⁵, 95 and as it nears the outer end of the stroke the first port to be opened is the exhaust port B² which is connected with an exhaust pipe H by a conduit b' passing through the water jacket and a conduit f in the walls of the casing F. In the wall of the sleeve A is a port A² which opens communication between the port B² and the exhaust preferably before the piston reaches the outer end of its stroke and allows the gases in the cylinder 105 to escape to atmosphere and the pressure in the cylinder to fall approximately to atmospheric level. When the piston is at the outer end of its stroke the port A² has passed the port B² which is again closed. When the 110 piston has reached the end of its stroke it uncovers the exhaust port B³ and thus opens

communication between the interior of the cylinder and the vacuum chamber E.

The vacuum chamber E is formed by a flange B⁶ on the outer end of the cylinder 5 B, part of the walls of the sliding member A, the walls d of the piston and the annular flange D' on the end of the piston D. During the initial part of the return stroke of the piston, the port B³ is closed and the 10 vacuum chamber is placed in communication with the exhaust port B⁴ by means of the port A³ in the member A so that the gases remaining in the cylinder are expelled at the commencement of the compression or 15 return stroke of the piston.

The outer casing F is secured to a base or bed J as is conveniently longer than the cylinder B, which it surrounds.

The inner end of the cylinder is secured 20 to the upper end of the casing F by bolts F' or in other appropriate manner so that the cylinder is suspended from this outer casing F in place of being bolted down to a bed plate as has hitherto been the case.

25 B¹⁰ is a cap or end piece which is fitted into the end walls of the cylinder and between it and the end B⁵ of the cylinder is a water cooling chamber. The sparking plug S is secured in the cap B¹⁰ and is in 30 communication with the combustion chamber by a conduit b⁵.

What I claim is:—

1. In an internal combustion engine the combination of a cylinder having inlet and 35 exhaust ports, a piston, a water cooling chamber or jacket surrounding the cylinder, a port controlling member located outside the water jacket, means for moving the port controlling member simultaneously with the 40 piston, and means for supporting the cylinder from its inner end.

2. In an internal combustion engine the combination of a cylinder, a piston in the cylinder, a water jacket surrounding the 45 cylinder, inlet and exhaust conduits communicating with the cylinder and terminating outside the water jacket, a ported sliding member controlling the inlet and exhaust and situated outside the water jacket, means 50 for moving the port controlling member simultaneously with the piston, means for suspending the cylinder from its inner end, a vacuum creating chamber and means whereby the inlet and exhaust port controlling member, also controls communication 55 between the cylinder and the vacuum creating chamber.

3. In an internal combustion engine, the combination of a cylinder, a piston, a water 60 jacket surrounding the cylinder, inlet and exhaust conduits communicating with the cylinder and terminating outside the water jacket, a vacuum creating chamber, a conduit leading from the outer end of the cylinder to the vacuum chamber, an exhaust port

for the chamber, a port controlling member situated outside the water jacket and having ports controlling in timed relation the inlet, exhaust and vacuum chamber, exhaust ports, means controlling the port between the cylinder and the vacuum chamber and means for moving the port controlling member simultaneously with the piston. 70

4. In an internal combustion engine the combination of a cylinder, a piston, a water 75 jacket located outside the cylinder, inlet and exhaust ports for the cylinder terminating on the outside of the water jacket, a collapsible vacuum creating chamber, a conduit leading from the cylinder to the vacuum 80 chamber an exhaust port for the chamber, a port controlling member situated outside the water jacket and having ports controlling in timed relation the inlet, exhaust and vacuum chamber, exhaust ports, means controlling the port between the cylinder and vacuum chamber and means for moving the port controlling member simultaneously with the piston. 85

5. In an internal combustion engine the 90 combination of a cylinder, having inlet and exhaust ports, a piston, a vacuum chamber, a flange on the piston forming one end wall of the chamber, a flange on the cylinder forming another wall of the chamber, a conduit 95 through the cylinder wall controlled by the piston, and connecting the cylinder and the vacuum chamber, an exhaust port in the vacuum chamber and means operated simultaneously with the piston for controlling the cylinder inlet and exhaust ports and the inlet to the vacuum chamber. 100

6. In an internal combustion engine, the combination of a cylinder, a piston, a water 105 jacket surrounding the cylinder inlet and exhaust ports communicating with the cylinder and terminating on the outside of the water jacket, a sleeve mounted to slide on the outside of the water jacket, and having ports controlling the inlet and exhaust ports 110 of the cylinder, means connecting the sleeve with the piston, a vacuum creating chamber a conduit between the cylinder and the vacuum chamber, means controlling this conduit, an exhaust conduit for the vacuum 115 chamber and a port in the sleeve for controlling this exhaust conduit.

7. In an internal combustion engine, the combination with a cylinder, having inlet and exhaust ports, a piston, a water jacket 120 inclosing the cylinder, a vacuum chamber, a flange on the piston forming one wall of the vacuum chamber, a flange on the cylinder forming another wall of the chamber, a conduit leading from the cylinder to the 125 vacuum chamber, an exhaust port in the vacuum chamber, a sliding sleeve surrounding the water jacket, and having ports controlling the cylinder inlet and exhaust ports, and the exhaust port in the vacuum chamber 130

and means connecting the sleeve with the piston.

8. In an internal combustion engine the combination with a cylinder having inlet and exhaust ports, a piston, a water jacket surrounding the cylinder, a port controlling sleeve mounted to slide on the outside of the water jacket and a flange on the piston to which the sleeve is connected to be operated by the piston.

9. In an internal combustion engine, the combination with a cylinder having inlet and exhaust ports, a piston, a water jacket surrounding the cylinder, a reciprocating 15 port controlling sleeve mounted on the out-

side of the water jacket, a vacuum creating chamber having ports communicating respectively with the cylinder and with the atmosphere, a flange on the cylinder forming one end wall of the chamber, a flange on the piston forming the other end wall of the chamber, means connecting the sleeve with the flange on the piston, means whereby the piston controls communication between the cylinder and the chamber, means whereby the sleeve controls in timed relation the inlet port to the cylinder the exhaust port of the cylinder and the exhaust port of the chamber.

ALFRED JAMES JUNG.
